UNITED STATES PATENT OFFICE.

NILS NILSON, OF SAN FRANCISCO, CALIFORNIA.

INK-FOUNTAIN FOR PRINTING-PRESSES.

SPECIFICATION forming part of Letters Patent No. 707,625, dated August 26, 1902.

Application filed April 10, 1901. Serial No. 55,265. (No model.)

To all whom it may concern:

Be it known that I, NILS NILSON, a citizen of the United States, residing in the city and county of San Francisco, State of California, 5 have invented certain new and useful Improvements in Ink-Fountains for Printing-Presses; and I do hereby declare the following to be a full, clear, and exact description of the same.

10 My invention relates to that class of ink-fountains for printing-presses in which an ink-containing receptacle provided with suitable discharges is so disposed relatively to the printing-press as to supply ink to the ink 15 receiving or distributing devices of the press. Though my invention is applicable to various presses, it is especially designed for use in connection with such presses as employ a distributing-roll which has a movement to and 20 from contact with the surface to be inked, such as that printing-press known as the "Rotary Neostyle Mimeograph;" and the object of my invention is to provide an ink-fountain in which the supply of ink delivered from 25 is controllable according to the character of the ink employed, said supply being automatic, its delivery guarded, controlled, and well distributed, and the whole device so constructed and mounted as to remain in proper 30 position relatively to the movable distributing press-roller which it supplies.

My invention consists in the novel constructions, arrangements, and combinations of parts, which I shall hereinafter fully describe 35 and claim.

Referring to the accompanying drawings, Figure 1 is a plan of my ink-fountain, a portion of the valve-plate E being broken away to expose the discharge-holes K in the bottom 40 of the ink-receptacle. Fig. 2 is an end elevation of the device, showing it in connection with the ink-distributing roller R. Fig. 3 is a cross-section on the line x y of Fig. 1, the valve-plate being shown partly raised, the handle C being thrown over to its locked position 45 with pin c'.

D represents the ink-containing receptacle, provided in its bottom with discharge-holes K. Within the receptacle D is hinged, as 50 shown in Fig. 3, the valve-plate E, which is adapted to lie down flat in the bottom of the

receptacle and to be raised up therefrom at an inclination to control the supply of ink to the discharges, as I shall presently describe. The under surface of the valve-plate is provided 55 with a washer-pad F, and through both plate and pad are made relief-openings G. (Shown clearly in Fig. 1.) The movement of the hinged valve-plate E is effected by the handle C, and the inclination of the plate is ad- 60 justably fixed or determined by a series of small holes c, Fig. 1, made in the handle C, and which are adapted to fit over a pin c', Fig. 3, in the top of the ink-receptacle D, so that the plate E may be raised and locked at 65 different inclinations. Pivoted by swinging links J to the ends of the ink-receptacle D is the ink-spreading roller H. The downward swing of this roller is limited by the stud j on the receptacle end, Fig. 2, and with which the 70 link J of the roller comes in contact. There is a stud j on each end of receptacle D. Secured to the ink-receptacle on the side opposite to the spreading-roller H is a downwardly-extending guard or splasher plate L. 75

A represents the hangers by which the ink-fountain is suspended. These hangers are provided with hooks a or similar devices, which are adapted to engage with any suitable part of the frame (unnecessary herein to 80 show) of the printing-press. These hangers are connected by a cross-bar B, Fig. 1. The ink-fountain is suspended both adjustably and yieldingly from these hangers by means of screw-studs N, which screw down into the 85 arched ends of the ink-receptacle D and are headed freely through the hangers. By means of these screw-studs the height at which the fountain is suspended can be regulated to define its proper position relatively 90 to the roller R of the printing-press. Springs M, Fig. 2, encircling the screw-studs N, lie between the arched ends of the ink-receptacle and the ends of the hangers A and permit the receptacle to yield upwardly under 95 the pressure of the movable press distributing-roller R if by chance the relative adjustment of the two be inaccurate and the roller R should come in contact with the ink-receptacle, thus avoiding injury to either. 100 The movement of the roller R to and from the ink-receptacle, but without touching it,

is indicated by a comparison of Figs. 2 and 3. Also by such comparison, if the roller R be supposed to have touched the ink-receptacle, the upward yielding of the receptacle is indicated. The roller R may represent any ink-receiving device of the printing-press, and its upward movement, as indicated, is sufficient to show the application of my device to the style of press heretofore mentioned.

The operation of the ink-fountain is as follows: The hangers A must be supposed to be connected with a suitable portion of the press-frame and be stationary though readily applied and removed, as indicated by their hooks a. The whole device is adjustably and yieldingly suspended in position relatively to the distributing-roller R, as shown in Figs. 2 and 3—that is to say, knowing the extent of the upward movement of the press-roller R the screw-studs N are so set as to suspend the ink-receptacle D at such a height that the roller R at the limit of its upward movement will not touch or wipe the under surface of the receptacle, but, as shown in Fig. 3, will approach thereto only closely enough to contact with and to receive the globules or drops of ink projecting from the discharges K. By screwing studs N up or down the proper position of the fountain can be had in every case; but to provide against injury of the parts, if by reason of an inaccurate adjustment the roller R should come in contact with the ink-receptacle, the spring M will permit the latter to yield under the contact. Ink is supplied to receptacle D, and when the valve-plate E is flat on the bottom of the receptacle the ink-discharges K are closed; but in practice if the valve-plate is allowed to lie loosely on the bottom a small supply of ink will pass through. With thicker ink the valve-plate is lifted up at an inclination and there held by its handle C engaging the pin c'. If the plate be raised to a greater inclination, still thicker ink can be fed. The apertures G in plate E prevent suction and also prevent the plate in lifting from rising and tending to spill the ink out of the receptacle D. The roller H, being freely hung, remains in contact with the roller R at all times, and being limited in its downward swing by the stud j it can never swing so low as to be in the way of or obstruct said roller R. The object of roller H is to spread the ink on roller R, preventing drops or larger masses by spreading them out. The guard-plate L insures against splashing of the ink by roller R over on that side.

Having thus described my invention, what I claim as new, and desire to secure by Letters Patent, is—

1. In an ink-fountain for printing-presses, the combination of the ink-receptacle having discharges in its bottom, the hinged valved plate in the bottom of the receptacle and controlling the supply of ink to the discharges, the handle by which the valve-plate is lifted to

an inclination with the bottom, and means for adjustably locking said handle to hold the valve-plate at different inclinations.

2. In an ink-fountain for printing-presses, the combination of the ink-receptacle having discharges in its bottom, the freely-swinging spreading-roller carried by the ink-receptacle on one side and the guard-plate depending from said receptacle on the other side.

3. In an ink-fountain for printing-presses, the combination of the ink-receptacle having discharges in its bottom, the adjustable valve-plate within the ink-receptacle for controlling the supply of ink to the discharges, the freely-swinging spreading-roller carried by the ink-receptacle on one side and the guard-plate depending from said receptacle on the other side.

4. In an ink-fountain for printing-presses, the combination of the ink-receptacle having suitable discharges, fixed hangers, screw-studs adjustably fitted to the receptacle and passing freely through the hangers, and springs encircling the screw-studs whereby the receptacle is adjustably and yieldingly suspended.

5. In an ink-fountain for printing-presses, the combination of the ink-receptacle having discharges, the freely-swinging spreading-roller carried by the receptacle on one side, the guard-plate depending from the receptacle on the other side, fixed hangers, and adjustable suspending devices connecting the receptacle with the hangers, for regulating the height of the receptacle relatively to the part to be inked.

6. In an ink-fountain for printing-presses, the combination of the ink-receptacle having discharges, the freely-swinging spreading-roller carried by the receptacle on one side, the guard-plate depending from the receptacle on the other side, fixed hangers, and spring-controlled adjustable suspending devices yieldingly connecting the receptacle with the hangers, for regulating the height of the receptacle relatively to the part to be inked.

7. In an ink-fountain for printing-presses, the combination of the ink-receptacle having discharges in its bottom, the adjustable valve-plate within said receptacle for controlling the supply of ink to the discharges, the spreading-roller swung from one side of the ink-receptacle, the guard-plate depending from its other side, fixed hangers, and adjustable suspending devices connecting the ink-receptacle with the hangers for regulating the height of the receptacle relatively to the part to be inked.

8. In an ink-fountain for printing-presses, the combination of the ink-receptacle having discharges in its bottom, the adjustable valve-plate within said receptacle for controlling the supply of ink to the discharges, the spreading-roller swung from one side of the ink-receptacle, the guard-plate depending from its other side, fixed hangers, and spring-con-

trolled adjustable suspending devices yield-
ingly connecting the ink-receptacle with the
hangers for regulating the height of the re-
ceptacle relatively to the part to be inked.

5 In witness whereof I have hereunto set my
hand.

In testimony whereof I have signed my

name to this specification in the presence of
two subscribing witnesses.

NILS NILSON.

In presence of—

A. D. SHEPARD,

J. T. MINSON.
